UNITED STATES PATENT OFFICE.

FRANK H. HOWARD, OF READING, PENNSYLVANIA.

CHAIN-STRETCHING MACHINE.

1,249,628.

Specification of Letters Patent. Patented Dec. 11, 1917.

Application filed July 5, 1917. Serial No. 178,670.

To all whom it may concern:

Be it known that I, FRANK H. HOWARD, a citizen of the United States, residing at Reading, in the county of Berks and State 5 of Pennsylvania, have invented certain new and useful Improvements in Chain-Stretching Machines, of which the following is a specification.

This invention relates to improvements in 10 chain stretching machines and the object of the invention is to facilitate the stretching of chain links to the desired size in such manner that a plurality of links may be stretched at one time instead of subjecting 15 each link individually to the action of stretching, as has been done heretofore.

The invention contemplates a machine in 20 which a section comprising a number of links may be stretched to the desired size by means of a drawing or pulling action, and in providing a mold or form block provided with receptacles for each link, so that the chain is not only stretched more rapidly, but in which the enlargement of each link is such 25 that the result is a uniform enlargement of the links and in which the result is accurate.

The invention consists of a machine comprising a mold, one end of which is adapted 30 to engage one of the links, while a movable pulling block is adapted for engagement with another link, remote from the one so first engaged, and means for giving the pulling block the desired movement to stretch the section of chain between the two points so 35 held until each link in said section enters one of the receptacles between the said two points.

A further object is to provide means for 40 adjusting the parts to accommodate different size chains, and also to regulate the distance of travel of the pulling member.

The invention is more fully described in 45 the following specification and clearly illustrated in the accompanying drawing in which:

Figure 1 is a plan view of my improved machine.

Fig. 2 is a longitudinal sectional view taken on the line 2—2 of Fig. 1.

50 The numeral 1 designates the machine frame, which is provided with a top plate 2. On the top of this plate I provide a pair of parallel, longitudinal guides 3 and between the guides is located a removable mold or form block 4. This mold is formed with a head 5 adapted to lie between and to be

held by the two arms of a clamp member 6. This clamp member is provided with a set screw 7 by means of which the mold block 4 may be adjusted on the top plate 2. The 60 clamp is provided with one or more guides 7^a which move in the lug 8 formed on the under side of the plate 2 and into which lug the screw 7 enters. The mold 4 is also provided with a centrally disposed longitudinal groove 9 and with a series of oppositely disposed pockets 10 along the edges of this groove, and these pockets together with the groove are intended to accommodate the links of the chain. 70

The numeral 11 designates the pulling block, the upper surface of which is also provided with a groove 12, in line with the groove 9 of the block 4, and with an upward extension forming a portion of two 75 link pockets, 13. This pulling block has a depending jaw 14 which is pivotally mounted at 15 between two lugs 16 on the under side of the plate 2.

The numeral 17 designates a power shaft, 80 and the letter G designates a train of gears, mounted on the shafts 17, 18 and 19 for transmitting rotation to the shaft 19, and on this latter shaft is mounted an eccentric 20 provided with a strap 21 having a rod 85 22 projecting upward therefrom and carrying a jaw 23, vertically adjustable thereon by means of nuts 24. To the upper end of the jaw 23 is pivotally attached a link 25 pivotally mounted on a lug 26 on the under 90 side of the plate 2.

To the upper end of the jaw 23 is also pivotally mounted a pair of arms 27 the opposite ends of which are in turn pivotally mounted at 28 to the jaw member 14 of the 95 pulling block 11.

When power is applied through the gears G to the shaft 19, the eccentric 20 will cause the jaw 23 to move vertically and thus produce a rocking movement of the pulling block 100 11, and the adjustment of this pulling block, that is, the starting point of the "pull" is regulated by means of the nuts 24.

When the chain section is to be stretched, one of the links is placed in the end pocket 105 "A" of the mold block 4 and the link at the opposite end of the section is dropped over the pulling block into the pocket 13. The movement of the block 11, around its pivotal center 15 will draw the chain, stretching each link until it falls into the pocket 10 beneath it, and the return movement of

the pulling block will permit the stretched section to be lifted out of the mold and the next adjoining section placed into position.

In the manufacture of chain, the links are 5 made smaller than the desired size, and by means of my present machine the stretching is done uniformly, accurately and rapidly.

As indicated, the amount of "pull" required is easily obtained, by means of adjusting the mold block toward or away from the pulling block, which is accomplished by 10 the screw 7.

The mold block is removable, so that 15 chains of different size links may be accommodated.

It is evident that the device above described may be made in different sizes, and that the machine may be otherwise modified without departing from the essential feature 20 of my invention, and I do not therefore desire to limit myself to the exact details of construction shown, but,

What I claim and desire to secure by Letters Patent is:—

1. In a machine of the character described, 25 a frame, a pair of guides, a mold block adjustably secured between the guides, a pulling member in line with the mold, means

on the pulling member for engaging one link of a chain and means for adjusting said pulling member relatively to the mold.

2. In a machine of the character described, the combination of a frame, a plate therefor, a pair of guides on the plate, a removable mold block located between the guides, 30 means for adjusting said block longitudinally between the guides, a pulling block pivotally mounted on the machine in line with the mold block, and means including an eccentric, a jaw and a pair of arms for 35 transmitting a regular movement to said pulling block.

3. A chain stretching machine comprising a frame, a chain mold block adjustably located thereon, a pulling member pivotally mounted on the frame, a pair of arms pivotally attached to the pulling block, an eccentric, a jaw carried by the eccentric and in pivotal connection with the opposite ends of said arms and means for conveying motion to the eccentric whereby the movement thereof will cause the pulling block to move 40 toward and away from the chain mold block.

In testimony whereof I affix my signature.

FRANK H. HOWARD.
